UNITED STATES PATENT OFFICE.

WILLIAM H. CRUTTENDEN AND MILTON E. CARD, OF CAZENOVIA,
NEW YORK.

DESIGN FOR A FLYING TARGET.

SPECIFICATION forming part of Design No. 17,419, dated June 28, 1887.

Application filed May 2, 1887. Serial No. 236,887. Term of patent 3½ years.

To all whom it may concern:

Be it known that we, WILLIAM H. CRUTTENDEN and MILTON E. CARD, citizens of the United States, residing at Cazenovia, in the county of Madison and State of New York, have invented and produced a new and original Design for Flying Targets, of which the following is a specification, reference being had to the accompanying drawings, forming a part

10 thereof, in which—

Figure 1 is a bottom plan view, and Fig. 2 a top plan, of a flying target provided with our design. Fig. 3 is a detail in vertical section.

15 Like letters indicate like parts in all the figures.

Heretofore targets of this class have been made plain on their concave or under surfaces, and with ridges or ribs upon their outer or con-

20 vex surface.

Our design consists in providing the concave or undersurface, A, with radiating grooves D, beginning at or near the rim B and converging toward the center and ending about midway thereof. Upon the opposite or convex surface we form concentric grooves E at suitable distances apart and of annular outline.

What we claim is—

The design for flying targets, the same consisting of a concavo convex shell having upon its concave face grooves converging from its rim toward the center and upon its convex surface concentric circumferential grooves, as shown and described.

WILLIAM H. CRUTTENDEN.

MILTON E. CARD.

In presence of—

W. L. DOREMUS,

CHAS. M. POTTER.
